UNITED STATES PATENT OFFICE.

CHARLES W. SMITH, OF SAN ANTONIO, TEXAS.

CHARGE-MOISTENING DEVICE FOR INTERNAL-COMBUSTION ENGINES.

1,359,761.

Specification of Letters Patent. Patented Nov. 23, 1920.

Application filed September 18, 1919. Serial No. 324,639.

To all whom it may concern:

Be it known that I, CHARLES W. SMITH, a citizen of the United States, residing at San Antonio, in the county of Bexar and State of Texas, have invented a new and useful Improvement in Charge-Moistening Devices for Internal-Combustion Engines, of which the following is a specification.

This invention relates to attachments for 10 automobiles, and more particularly to a device having communication with the engine thereof, for reducing to a minimum, carbon deposit within the cylinder, and on the valve members thereof.

15 A further object of the invention is to direct the gas which collects in the crank case of the engine, to the engine cylinders where the same is used as fuel, thereby rendering the engine more powerful, with a given 20 quantity of gas.

25 A further object of the invention is to provide a device of this character which may be efficiently employed as a priming device, if so desired, to facilitate the starting 25 of the engine in cold weather.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without 35 departing from the spirit of the invention.

Referring to the drawings:—

Figure 1 illustrates a side elevational view of an automobile, the same being shown as partly broken away, to disclose the relation 40 of the invention with the engine.

Fig. 2 illustrates a front plan view of the tank used in connection with the engine,

Fig. 3 illustrates a sectional view taken on line 3—3 of Fig. 2.

45 Fig. 4 illustrates a transverse sectional view taken on line 4—4 of Fig. 3.

Referring to the drawings in detail, the reference character 5 designates the dash board of an automobile, supplied with the 50 device forming the subject matter of the present invention.

The dash board 5, is provided with a central bore 6, through which extends the pipe 19, which has communication with the mani-

fold of the engine, as at 20, for supplying the 55 engine with gas, in the event that the device is to be employed as a primer.

The dash board 5 is also provided with lateral bores 9 and 10, each of which accommodates a pipe 11, which has its ends threaded as at 12, one of said ends of one pipe being internally threaded to receive the threaded end 14 of the pipe 15, which has connection with the water jacket of the engine, as at 16, and it will be seen that due to the 60 connection between the pipe and water jacket, the steam, generated in the water jacket, is carried off through said pipe 15.

The opposite pipe, is also internally screw threaded to receive one end of the pipe 17, 70 which has communication with the crank casing, as at 18, whereby the gases which ordinarily collect in the crank casing, may be drawn off, and admitted to the cylinders of the engine, through pipe 19, which as 75 shown has connection with the manifold of the engine, as at 20.

Each of the pipes, is in communication with a supporting member 21, which is in the form of a block, and is provided with a 80 plurality of bores 22, which have connection with the respective pipes 15, 17, and 19. The block 21, is provided with an annular groove 23, formed in the upper surface thereof, which groove accommodates a packing 24, 85 to prevent leakage between the glass cylinder 25, which forms the body of the receptacle, the lower ends of said cylinder 25, being disposed within the annular groove 23, and held therein, by means of the elongated rod 26, having a threaded end 27 operating in a threaded opening formed in the upper surface of the block 21.

Disposed on the upper edge of the cylinder 25, is a cover 29, which is provided 95 with an annular depending flange 30, adapted to embrace the cylinder adjacent the upper end thereof, said cover being held to the upper end of the cylinder 25, by means of the rod 26, due to the flange 31, engaging 100 with said cover, when the rod is positioned to hold the cylinder 25 to its seat, within the block 21.

This rod 26, is also provided with a head 32, which head has upwardly extending 105 flanges 34, forming a funnel, to direct fluid to the bore 35, formed in the rod 26, the same terminating substantially intermedi-

ate the length of the rod, and having a lateral portion 36 providing communication between the bore, and the cylinder 25.

A valve member 37, is provided with a reduced end 38, intersecting the bore 35, to restrict the flow of fluid through the bore 35 formed in the rod 26.

The bores 22, extend through the block 21, and are provided with threaded portions 39, to receive the threaded portions 40 of the valve members 41 and 42 controlled by the springs 41' and 42', which valve members have reduced ends 43, extending into the bores 22, for cutting off the flow of fluid therethrough.

Each of the bores 22, is in communication with the cylinder 25, through the medium of the nozzles 44, which have one of their ends supported within the bores 45, also formed in the block 21, the upper ends of said nozzles 44, being curved as indicated at 46, whereby the flow of fluid through the nozzles, is directed downwardly toward the bottom of the cylinder 25.

From the foregoing it is obvious that when the engine is running, the suction caused by the pistons operating in their cylinders, causes steam to be drawn through the pipe 15, and deposited within the cylinder 25, at the same time the gases, which have collected in the crank case, are drawn into the cylinder 25, through the pipe 17, whereby the gases mingle with the steam or vapor, and are drawn into the engine, through the pipe 19, which as before stated, has connection with the manifold of the engine.

If it is desired to employ the device as a primer, it is only necessary to operate the valves 41 and 42, to close the pipes leading from the crank casing, and water jacket, fill the funnel with a sufficient quantity of gasolene, to prime the engine, and allow the same to flow downwardly into the cylinder 25, whereby the suction of the pistons within the cylinders, causes the priming charge to be drawn directly into the engine, where the same is fired, thus starting the engine.

Having thus described the invention, what is claimed is:—

In combination with a gas engine, the crank casing, water jacket, and manifold thereof, a receptacle including a cylinder supported adjacent the engine, a rod extending through the cylinder, and having a passage communicating with the interior thereof, a funnel disposed at the upper end of the rod, said funnel adapted to direct fluid through the rod, means for providing communication between the cylinder, crank casing, and water jacket of the engine, means for providing communication between the cylinder and manifold of the engine, whereby material is drawn from the crank casing and water jacket, into the cylinder, and discharged into the manifold of the engine.

In testimony that I claim the foregoing as my own, I have hereto affixed my signature in the presence of two witnesses.

CHARLES W. SMITH.
